UNITED STATES PATENT OFFICE.

NILS P. BOLIN, OF BROCKTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,309,716.

Specification of Letters Patent.

Patented July 15, 1919.

Application filed November 28, 1916. Serial No. 133,881.

To all whom it may concern:

Be it known that I, NILS P. BOLIN, a citizen of the United States, residing at Brockton, in the county of Plymouth and State of Massachusetts, have invented certain Improvements in Lasting-Machines, of which the following description, in connection with the accompanying drawings, is a specification, like reference characters on the drawings indicating like parts in the several figures.

This invention relates to lasting machines and particularly to mechanism to be applied to or incorporated in machines of the type known as bed lasting machines such as is shown, for example, in United States Letters Patent No. 1,018,477, granted February 27, 1912, on application of Matthias Brock.

In lasting the toe portion of a shoe upper upon machines of this type it is customary for the operator to close the toe lasting plates in at a point somewhat below the plane of the innersole and to press them against the upper on the last while he moves them upwardly. The pressure and friction of the lasting plates or wipers tend to smooth the upper out against the last, to draw it tight, and to gather in the fullness of the upper and carry it to a point above the plane of the last bottom. Frequently a hand tool, called a spreader, is employed to press the upper downwardly and outwardly over the top faces of the wipers to increase their tensioning and smoothing effect.

An object of this invention is to provide improved auxiliary lasting mechanism to be employed for producing more effective toe lasting in combination with the usual toe lasting head movable vertically and having forwardly and inwardly closing wipers.

A feature of the invention consists in the combination with a flexible spreader member which is adapted to be forced by hand against the margin of upper outwardly overlying the wipers, of improved means for expanding the spreader during the lasting operation. Preferably the expansion of the spreader is effected by relative movement of the toe lasting head and the wipers. This relative movement is produced in the construction shown by forward movement of the wipers which carry the spreader with them while the joint of a toggle remains stationary due to its being held from move-

ment by a non-extensible connection with the toe lasting head.

The foregoing and other features of the invention will appear more fully from the following description when read in connection with the accompanying drawings and will be pointed out in the appended claims.

Figure 1 is a perspective view of the lasting head of a bed lasting machine equipped with the spreader embodying this invention and shows the wipers closed and the end portions of the spreader expanded against the wipers;

Fig. 2 is a longitudinal sectional view; and

Fig. 3 is a plan view of the spreader mechanism.

The frame of the vertically movable toe lasting head is indicated at 2. This frame is mounted for vertical movement and is operated by means of a treadle 4 through suitable connections to move the wipers vertically in their upwiping action against the sides and end of the last. A frame 6 is pivoted to the frame 2 at 8 about which pivot the wipers may be adjusted to the longitudinal inclination of the last bottom by means of a screw 10. The wiper box 12 has a sleeve 14 journaled in the frame 6, the sleeve being adjustable about its longitudinal axis by means of a screw 16 to vary the lateral inclination of the wipers in accordance with the transverse inclination of the last bottom. Through the sleeve 14 a wiper operating rod 18 extends which is moved longitudinally by a lever 20. At the inner end of the rod 18 is a cross piece 22 which is connected to wiper carriers 24 by links 26. Movement of the wiper carriers 24 is controlled by slots 28 which are engaged by rolls 30 mounted on studs 32 fixed in the box 12. Upon the carriers 24 are rigidly mounted wipers 34.

The toe of the shoe is supported by a toe rest 40 upon which it is firmly held by a hold-down arm 42 having a finger 44 extending toward the toe and acting to hold down the toe portion of the innersole.

The spreader comprises a support 50 having a handle 52 secured to it at one end and at the other end carrying a spreader member 54 rigidly secured to it. The spreader member 54 preferably comprises a relatively thin flexible and resilient strip or plate so ar-

ranged that one edge may be presented to the margin of upper which lies over the wipers and against which it may be held by the handle 52. The normal or unexpanded 5 shape of the spreader member is shown in Fig. 3. The spreader has this shape while the upper is being wiped up the sides of the shoe, the more sharply curved part being pressed against the central part of the toe 10 portion of the upper and causing a longitudinal stretching of the upper to accompany the upward wiping action of the wipers. The ends of the spreader member 15 54 are connected by a toggle comprising links 56, 57 which are pivoted to a block 58. The block 58 carries an eye-bolt 60 which is connected to a pin 62 on the wiper box 12 by a non-extensible link rod 64 which passes through an opening in the frame 50. The 20 pin 62 is connected to the frame 50 by yielding or extensible connections shown as comprising a spring 66 and a link rod 68. When the lower face of the wipers reaches the 25 plane of the upper surface of the innersole and begins to advance on to the feather of the innersole, the spreader, by its frictional contact with the upper, is carried toward the heel of the shoe relatively to the joint of the toggle 56, 57, causing the toggle to 30 straighten and the spreader member 54 to be expanded laterally, its end portions pressing the upper against the inwardly closing wipers and applying an additional tension to the upper at the corners and sides of the 35 toe. The straightening of the toggle acts to reduce the curvature of the spreader and to carry the end portions outwardly against the upper at the corners of the toe. Since the closing movement of the wipers accompanies their movement of advance over the 40 shoe bottom and the advance of the wipers automatically effects the lateral expansion of the spreader, the wipers and end portions of the spreader mutually approach each 45 other and cause the upper to be firmly gripped and held at the corners of the toe between the wipers and the spreader as the wipers close and the lasting and tensioning effect of the wipers is thereby materially increased. By means of the handle 52 the 50 operator has the lateral clamping action of the spreader under his control and may relieve it by lessening downward pressure on the spreader handle in case, in his judgment, 55 the upper is being too firmly held for lasting the particular shoe which is being operated upon.

Having thus described my invention, I claim as new and desire to secure by United 60 States Letter Patent:

1. Toe lasting mechanism having, in combination, a toe head, inwardly moving wipers thereon, an expansible spreader, manual means for holding the spreader against the center of the upper at the toe, and means 65

operating in response to movement of the wipers for expanding the spreader to clamp the upper at the corners of the toe.

2. Toe lasting mechanism having, in combination, a vertically movable head, inwardly moving wipers thereon, an expandable spreader, manual means for holding the spreader against the center of the toe during upward movement of the head, and means operated by the wipers for expanding 75 the spreader to clamp the upper against the wipers at the corners and sides of the toe during the inward movement of the wipers.

3. Toe lasting mechanism having, in combination, a vertically movable head, inwardly moving wipers thereon, an expandable spreader, manual means for holding the spreader against the wipers at the center of the toe during the vertical movement of the head, and means operated by the wipers in 80 their advancing movement for expanding 85 the spreader to press the upper against the wipers at other portions of the toe.

4. Toe lasting mechanism having, in combination, a toe head, inwardly moving 90 wipers thereon, an expansible spreader, and means operated by the wipers in their advancing movement to expand the spreader to clamp the upper against the wipers.

5. A lasting machine having, in combination, a vertically movable toe head, inwardly moving wipers, a spreader, operating means for the spreader to force the upstanding marginal portion of the upper against the wipers at the end of the toe during vertical 100 movement of the head for stretching the upper, and means operating without special attention on the part of the operator, for thereafter progressively advancing the spreader to continue its operative action toward the ends of the wipers at the sides of the toe.

6. A lasting machine having, in combination, a toe head, inwardly moving wipers, a spreader, operating means for forcing the 110 upstanding marginal portion of the upper against the wipers at the end of the toe, and means operated by the wipers in their inward movement for progressively extending the operating action of the spreader toward 115 the ends of the wipers at the sides of the toe.

7. A lasting machine having, in combination, end embracing wipers, means for advancing and closing the wipers, a toe head fixed relatively to the wiper movement, a 120 spreader comprising a resilient curved plate presented edgewise to the upper on the wipers, yielding means connecting the plate to the toe head, manual means for pressing the plate against the upper on the wipers at 125 the center of the toe, and means operated by the wipers in their advancing movement for straightening the plate to apply clamping pressure to the upper at the corners of the toe.

8. Toe lasting mechanism having, in combination, toe embracing wipers, operating means for advancing and closing the wipers, a spreader arranged to clamp the upper in 40
5 outspread condition over the wipers, and means operating without attention on the part of the operator for causing the spreader to be expanded to clamp the upper at the corners of the toe during movement of the
10 wipers over the shoe bottom.
9. Toe lasting mechanism having, in combination, toe embracing wipers, operating means for advancing and closing the wipers, an expansible spreader, and means controlled by the wiper movement for expanding the spreader laterally to spread the upper at the corners and sides of the toe.
10. Toe lasting mechanism having, in combination, toe embracing wipers, operating means for advancing and closing the wipers, 45
20 a head carrying the wipers, an expansible spreader, a yielding connection between one part of the spreader and the head, and a positive connection between another part
25 of the spreader and the head whereby movement of the yieldingly held part with the wipers relatively to the positively held part will effect lateral expansion of the spreader to clamp the upper against the wipers at the
30 sides of the toe.

11. Toe lasting mechanism having, in combination, toe embracing wipers, operating means for advancing and closing the wipers, a spreader having a continuous edge for 50
35 contact with the upper on the wipers extending from the center of the toe past the corners of the toe, manual means for forcing the spreader against the upper at the center of the toe, and means operating without

the operator's attention for causing the corner extensions of the spreader to approach 40
the wipers as the wipers close.

12. Toe lasting mechanism having, in combination, a vertically movable lasting head, 45
forwardly and inwardly moving wipers, operating means for forcing the upper outwardly against the portion of greatest curvature of the wipers during the upward movement, and means operated by the wipers in their movement for forcing the upper 50
outwardly against the straighter portions of the wipers at the two sides of the toe.

13. A lasting machine having, in combination, a toe head, a spreader support mounted on the head for movement longitudinally 55
of the shoe against spring tension, a spreader secured to the support and composed of a continuous, flexible, curved band having its edge face presented toward the work, and non-extensible connections between the ends 60
of the band and the toe head for causing the band to straighten when the band and head are moved relatively.

14. A lasting machine having, in combination, a toe head, a spreader support, a flexible, longitudinally extensible connection between the spreader support and the toe head, 65
a spreader comprising a resilient bowed flat spring secured to the support and presenting the edge face of the spring to the work when 70
in operative position, and non-extensible connections between the ends of the spring and the toe head to cause straightening of the spring when the support and toe head are moved relatively longitudinally of the shoe. 75

In testimony whereof I have signed my name to this specification.

NILS P. BOLIN.
